ELECTRIC IRONER AND DAMPENER

Max Skolnik, Chicago, Ill.

Application March 1, 1933, Serial No. 659,067

9 Claims. (CL. 68—26)

This invention relates to electric irons and more particularly to combination electric ironer and dampener for pressing and ironing clothes.

The main objects of this invention are to provide a combination electric ironer and dampener; to provide an article of the class described having a water reservoir attached to the iron and forming a part thereof; to provide a thermal insulator which is located between the water reservoir and the heating element; to provide an ironer and dampener having a circuitous groove in the shoe of the iron; to provide a conduit leading from the reservoir; to provide a plate for covering the shoe of the iron; to provide a valve mechanism for controlling the amount of water deposited in the groove; to provide a chamber having apertures extending outwardly therefrom; and to provide an ironer and dampener which will emit dry steam.

20 An illustrative embodiment of this invention is shown in the accompanying drawings, in which:

Figure 1 is a top plan view of the iron.

Fig. 2 is a side view partly in section taken on the line 2—2 of Fig. 1.

25 Fig. 3 is a front view partly in section taken on the line 3—3 of Fig. 2.

Fig. 4 is a plan view partly in section taken on the line 4—4 of Fig. 2 and with parts broken away.

Referring in detail to the construction shown 30 in the drawings, the electric iron comprises a shoe 1, a cover plate 2, a handle 3, and a reservoir 4.

The shoe 1 is of special construction and is provided with a circuitous groove 5 and a chamber 6. The chamber 6 is provided with apertures 7 extending outwardly therefrom to the face 8 of the shoe 1 and adjacent the toe 1'.

The handle 3 is of the usual construction and is held in place by the brackets 9 and bolts 10.

40 The reservoir 4 is secured to the rear of the iron and over the heel 37 of the shoe 1 as shown in Figs. 1 and 2, and is provided with a water inlet 11 and an air vent 12. The reservoir 4 is constructed so that it requires a minimum amount of space

45 on the iron and is not appreciably larger than the ordinary iron. With this in mind, I have constructed the rear medial portion of the reservoir 4 in a U-shape so as to accommodate the plug 13 which is attached to an electrical supply source 50 (not shown) through wires 14, to the contact elements 15 of the iron. A bracket 16 is secured to the reservoir 4 for setting the iron on end in the usual way when the iron is not in immediate use.

A conduit 17 leads from the reservoir 4 to a valve mechanism which will be hereafter de-

scribed. A plate 18 is placed over the shoe 1 and forms a cover for the groove 5. A continuous channel is thereby formed. A heating element 19 is then placed over the cover plate and connected at one end to the contact elements 15 by a conductor 33. The heating element does not extend under the reservoir. An insulating plate 20 is then placed over the heating element and a holding plate 21 is placed over the insulating plate. The plate 21 is then fastened to the shoe 1 by any suitable means, such as screws 22, etc. (See Fig. 4.)

The reservoir 4 is thermally insulated from the shoe 1 by providing a plurality of longitudinal apertures 23 between the lower portion of the reservoir and above the heel 37 of the shoe 1 so as to allow air to pass freely therethrough.

A valve mechanism is disposed adjacent the front part of the iron and comprises a lever 25 which has a knob 24 attached to one end and a needle rod 27 pivotally attached at the other end through a linkage. (See Fig. 3.) The lever 25 is pivoted at 26 by any suitable means such as a bolt, etc.

The lower end of the rod 27 is conical shaped 80 and is adapted to fit snugly into aperture 28, and a helical spring 29 normally tends to hold the rod 27 in closed position, as shown in Figs. 2 and 3. A channel 30 connects the valve mechanism to conduit 17.

In operation the reservoir 4 is filled with water and plug 13, attached to an electric supply source, is connected to contacts 15, thereby delivering electrical energy to the heating unit 19. The water in the conduit 17 positioned adjacent the heating element, will thereby be preheated. When dry steam is to be emitted from the shoe, the knob 24 is depressed, the preheated water in conduit 17 will be forced upwardly through the aperture 28 and downwardly through channel 31 and be deposited in the groove or channel 5, and the water instantaneously becomes steam, due to the high temperature of the shoe.

As the steam passes through the circuitous groove 5, it becomes superheated, and by the time 100 it reaches chamber 6 it is dry steam which will be emitted through apertures 7 to the face of the shoe.

Metal wool 32 is placed in the chamber 6 to diffuse the flow of steam.

Although the water in the reservoir 4 will not be kept cool, it will not reach the boiling point under ordinary circumstances, but should this occur, the air vent 12 in the reservoir will provide an outlet through which the steam can escape.

105

110

Experience has proved that in ironers and dampeners having the water reservoir attached to the iron, means must be provided to prevent the rapid formation of steam in the reservoir. Having this in mind applicant provides a thermal insulator, shown particularly in Figs. 2 and 4, which is adapted to provide for free air circulation between the reservoir and the heating element, and serves to retard the transmission of heat to the water in the reservoir and keep the temperature of the water below the boiling point.

Although but one specific embodiment of this invention is herein shown and described, it is to be understood that some of the details as set forth may be altered or omitted without departing from the spirit of the invention as defined by the following claims.

I claim:

1. An electric steam iron of conventional plan design over the rearward heel part of which is provided a water reservoir, electric heating means housed in the body of said iron, said body having a water passage extending adjacent to said heating means and a steam passage extending circuitously from and communicating with said water passage and extending to the front part of said iron in which part is provided downward steam jet apertures with which said passage communicates, and a valve at the juncture between the two passages adapted and arranged for manual control to regulate the discharge of water from said reservoir through said passage.

2. An electric flat iron of the class described comprising a shoe, a water reservoir, a water conduit extending from said reservoir, a steam passage extending circuitously from and communicating with said water conduit and terminating in the toe part of said shoe, said water conduit being parallel to the plane of said steam passage, said toe part being provided with a chamber having apertures extending downwardly therefrom, a heating element disposed between said water conduit and steam passage, and means interposed between said water conduit and steam passage for controlling the amount of water entering said steam passage.

3. An electric flat iron of the class described comprising a shoe, a water reservoir, insulating means interposed between said reservoir and said shoe, a water conduit extending from said reservoir, a steam passageway extending circuitously from and communicating with said water conduit and terminating in the toe part of said shoe, said toe part being provided with a chamber having apertures extending downwardly therefrom, a heating element disposed between said water conduit and steam passageway, and means interposed between said water conduit and steam passage for controlling the amount of water entering said steam passage.

4. An electric flat iron of the class described comprising a shoe, a water reservoir located over the heel of the iron, insulating means interposed between said reservoir and said shoe, a water conduit extending from said reservoir, terminating in the fore part of said iron, a steam passage communicating with said water passage and extending circuitously rearwardly and forwardly and terminating in the toe part of said shoe, said toe part being provided with a chamber having apertures extending outwardly therefrom, a heating element disposed between said water conduit

and steam passage, and means interposed between said water conduit and steam passage for controlling the amount of water entering said steam passage.

5. An electric flat iron of the class described comprising a shoe, a water reservoir, insulating means interposed between said reservoir and said shoe, a water conduit extending from said reservoir and terminating in the fore part of said iron, a steam passage communicating with said water passage and extending circuitously rearwardly and forwardly, and terminating in the toe part of said shoe, said toe part being provided with a restricted chamber having apertures extending outwardly therefrom, a heating element disposed between said water conduit and steam passage, means interposed between said water conduit and steam passage for controlling the amount of water entering said steam passage and insulating means disposed between said water conduit and heating element.

6. In an ironer and dampener, a shoe, means for heating the same, a handle for the shoe, a water reservoir thermally insulated from said heating element and adjacent the rear support of said handle, a circuitous groove in said shoe, a cover plate for said shoe forming a steam passage through said shoe, a conduit connecting said reservoir with said passage, and a manually controlled valve in said conduit, said shoe being provided with a plurality of apertures in its face and communicating with said passage.

7. In an ironer and dampener, a shoe, means for heating the same, a handle for the shoe, a water reservoir thermally insulated from said heating element and adjacent the rear support of said handle, a circuitous groove in said shoe, a cover plate for said shoe forming a steam passage through said shoe, a conduit connecting said reservoir with said passage, a manually controlled valve in said conduit, an expansion chamber in the outlet end of said passage, and metal wool in said chamber, said shoe being provided with a plurality of apertures in its face and communicating with said passage.

8. In an ironer and dampener, a shoe, means for heating the same, a handle for the shoe, a water reservoir thermally insulated from said heating element and adjacent the rear support of said handle, a circuitous groove in said shoe, a plate between said shoe and said heating element, said plate being arranged and adapted to cover said groove in said shoe and forming a steam passage through said shoe, a conduit connecting said reservoir with said passage, a manually controlled valve in said conduit, an expansion chamber in the outlet end of said passage, and metal wool in said chamber, said shoe being provided with a plurality of apertures in its face and communicating with said passage.

9. In an ironer and dampener, a shoe, means for heating the same, a handle for the shoe, said shoe being provided with a circuitous groove, a plate disposed between said shoe and heating element, thereby forming a continuous passage through said shoe, and means for delivering water to said passage, the outlet end of said passage being provided with downwardly extending apertures communicating with the face of said shoe.

MAX SKOLNIK.
